FOREIGN PATENT DOCUMENTS

WO 2016054117 A1 4/2016

Primary Examiner — Katrina A Betton(74) *Attorney, Agent, or Firm* — Adam R. Stephenson, Ltd.(57) **CLAIM**

The ornamental design for a vehicle roll cage, as shown and described.

DESCRIPTION

FIG. 1 is a front perspective view of a first embodiment of a vehicle roll cage;

FIG. 2 is a front view of the embodiment of FIG. 1;
FIG. 3 is a rear view of the embodiment of FIG. 1;
FIG. 4 is a right side/passenger side view of the embodiment of FIG. 1;

FIG. 5 is a left side/drivers side view of the embodiment of FIG. 1;

FIG. 6 is a top view of the embodiment of FIG. 1;
FIG. 7 is a bottom view of the embodiment of FIG. 1;
FIG. 8 is a front perspective view of a second embodiment of a vehicle roll cage;FIG. 9 is a front view of the embodiment of FIG. 8;
FIG. 10 is a rear view of the embodiment of FIG. 8;
FIG. 11 is a right side/passenger side view of the embodiment of FIG. 8;

FIG. 12 is a left side/drivers side view of the embodiment of FIG. 8;

FIG. 13 is a top view of the embodiment of FIG. 8; and,
FIG. 14 is a bottom view of the embodiment of FIG. 8.
All broken lines represent unclaimed features of the article to which the design is applied.**1 Claim, 12 Drawing Sheets**(56)
